WILLIAM A. KELSEY, OF MINNEAPOLIS, MINNESOTA

DENTAL INSTRUMENT

Application filed October 10, 1927. Serial No. 225,358.

This invention relates to new and useful improvements in dental instruments, and particularly to such instruments comprising a handle portion having a tool demountably received in one end thereof, and, of the class generally used in the dental profession for scraping and cleaning teeth, preparing cavities, carving wax forms, and various similar operations.

- 10 An object of the invention is to provide a dental instrument comprising an elongated body providing a finger grip for the instrument and having a socket at one end thereof adapted to receive the shank of a tool, 15 and a stem being received in threaded engagement with the opposite end of the body and co-operating therewith to provide the handle for the instrument, and a locking member being pivotally mounted in said body 20 and having one end adapted to be engaged by the terminal of said locking screw whereby the locking member may be moved into locking engagement with the tool shank, to secure it to the body.
- 25 A further object of the invention is to provide a dental instrument comprising a body having a tool-receiving socket provided in one end thereof and arranged at a slight angle with respect to the axis of the body, 30 and a locking screw being received in threaded engagement with the opposite end of the body and co-operating therewith to provide a handle for the instrument, and a plate-like locking member being mounted 35 within said body and having one end arranged to be engaged by said locking screw, the opposite end of said locking member having means for engaging and gripping a tool shank, when the member is actuated by the locking screw, and said locking member also having an inclined face adapted to engage the end of the tool shank and translate it in an outward direction to partially remove it from the body, when said locking screw has 40 been moved out of engagement with the locking member, and the latter is actuated.
- 45 A further object is to provide a dental instrument of the class described comprising a handle portion having means for demountably receiving a dental tool, said instrument

being provided with a simple and efficient locking means for securing the tool shank in said handle portion, said locking means being conveniently operable, whereby a tool may be quickly removed from the handle and another one substituted therefor.

The particular object of the invention, therefore, is to provide an improved dental instrument of the class described.

Other objects of the invention will appear 60 from the following description and accompanying drawings and will be pointed out in the annexed claims.

In the accompanying drawings, there has been disclosed a structure designed to carry 65 out the various objects of the invention, but it is to be understood that the invention is not confined to the exact features shown as various changes may be made within the scope 70 of the claim which follow.

In the accompanying drawings forming part of this specification:

Figure 1 is a longitudinal sectional view of the improved instrument showing the locking member engaged with a tool shank to 75 lock the latter to the body;

Figure 2 is a similar view, slightly enlarged, showing the locking member in unlatching position, and further showing the means provided thereon for translating the 80 shank of the tool in an outward direction to remove it from the body;

Figure 3 is a cross sectional view on the line 3—3 of Figure 1;

Figure 4 is a cross-sectional view on the 85 line 4—4 of Figure 1; and

Figure 5 is a view showing the tool removed from the body.

The novel dental instrument featured in this invention comprises an elongated body 90 2, having a socket 3 provided at one end thereof adapted to receive the shank 4 of a tool 5, as shown. The axis of the socket 3 is preferably arranged at an angle with respect to the axis of the body 2 and is also 95 off-set therefrom as indicated by the dotted lines *a—a* and *b—b*. A notch 6 is terminally provided in the body 2 adapted to receive a tongue or flattened portion 7 provided upon the shank 4 of the tool. When the 100

notch 6 and tongue 7 are interlocked, the tool shank will be prevented from turning or rotating in the socket 3.

The means provided for securing the tool shank in the socket 3 consists of a locking member 8 mounted in an elongated recess 9, provided in the body 2. The locking member 8 is pivotally mounted upon a pin 10 as shown. A detent 11 is provided at one end of the locking member 8 and is adapted to be received in a notch 12 provided in the tool shank as shown, particularly in Figures 2 and 5. An inclined face 13 is also provided in the locking member 8 adjacent to the detent 11. This inclined face is adapted to engage a beveled face 14 provided at the end of the tool shank 4. The purpose of the beveled faces 13 and 14 is to provide means for translating the tool shank in an outward direction in the socket 3, when the locking member is moved into unlocking position, as shown in Figure 2.

A locking screw 15 is received in a threaded socket 16 provided at the opposite end of the body and has a cone-shaped terminal 17 adapted to engage the inclined face 18 of the locking member, as shown in Figure 1. The axis of the socket 16 is also off-set from the axis of the body 2 in the same direction as the axis of the tool-receiving socket 3. The locking screw has a stem 19 which co-operates with the body 2 to provide the handle for the instrument. A knurled head 20 is provided at the outer end of the stem 19 to provide means for conveniently rotating the screw 15 to move the terminal 17 into and out of locking engagement with the inclined face 18 of the locking member 8.

In the operation of this novel instrument, the shank 4 of the tool is inserted into the socket 3 until the tongue 7 is received in the notch 6 provided at the end of the body. The pivotal mounting of the locking member 8 within the recess 9 is such that when the tool shank is inserted into the socket 3, the beveled face 14 thereof, will engage the beveled face 13 of the locking member and cause the latter to be moved into locking position substantially as shown in Figure 1, when the tool shank reaches the position shown in this figure. The locking screw 15 is then rotated to move the terminal 17 into engagement with the inclined face or edge 18 of the locking member, thereby causing the locking member 8 to securely grip the tool shank and thus secure it to the body portion 2 of the handle. When it is desired to remove the tool shank from the socket 3 for the purpose of changing tools, and so on, the locking screw 15 is translated outwardly substantially to the position shown in Figure 2, after which the locking member 8 may be oscillated upon the pin 10 by applying a slight pressure thereto at the point indicated at P, thus causing the inclined face 13 of the latch member to move

the tool shank outwardly to the position shown in Figure 2, after which it may readily be withdrawn from the socket and a new tool inserted therein. One edge of the locking member 8 preferably extends beyond the periphery of the body 2, so that pressure may be applied thereto at the point P, when it is desired to remove the tool shank from the socket 3. The sockets 3 and 16 are preferably offset from the axis of the body 2, as hereinbefore stated, so that when the instrument is in use and pressure is brought to bear on the body 2 at the point indicated at P¹, there will be no tendency for the instrument to turn or rotate in the operator's hand.

I claim as my invention:

1. In a dental instrument, the combination of an elongated body shaped to provide a finger grip for the instrument, a tool-receiving socket in one end of said body having its axis disposed at an angle with respect to the axis of said body to prevent relative rotation of the instrument when held in the hand of an operator and lateral pressure is brought to bear thereon, a threaded socket in the opposite end of said body adapted to receive a locking screw, and a locking member mounted in said body and adapted to be engaged by said locking screw whereby said locking member may be moved into locking engagement with the tool shank to secure it to said body.

2. In a dental instrument, the combination of an elongated body shaped to provide a finger grip for the instrument, a tool-receiving socket in one end of said body arranged at an angle with respect to the axis of the body to prevent relative rotation of the instrument when held in the hand of an operator and lateral pressure is brought to bear thereon, a threaded socket in the opposite end of said body having a locking screw adjustably mounted therein, and a locking member mounted on said body and having one end arranged to engage and grip a tool shank inserted in said tool-receiving socket, and the opposite end of said locking member being adapted to be engaged by said locking screw to cause the member to secure the tool shank in said body.

3. In a dental instrument, the combination of a body forming a finger grip for the instrument, a tool-receiving socket in one end of said body arranged at an angle with respect to the axis thereof to prevent relative rotation of the instrument when held in the hand of an operator and lateral pressure is brought to bear thereon, a locking screw received in threaded engagement with the opposite end of said body, a recess in one side of said body, and a plate-like locking member or latch pivotally mounted within said recess and having one end adapted to engage a tool shank to lock the latter to said body said locking member having its opposite end adapted to be engaged by said locking screw, whereby

said locking member may be moved into locking engagement with the tool shank.

4. In a dental instrument, the combination of a body forming a finger grip for the instrument, a tool-receiving socket in one end of said body arranged at an angle with respect to the axis thereof to prevent relative rotation of the instrument when held in the hand of an operator and lateral pressure is brought to bear thereon, a locking screw received in threaded engagement with the opposite end of said body, a recess in one side of said body extending substantially the length thereof, and a plate-like locking member or latch pivotally mounted within said recess and having one end adapted to engage and grip a tool shank to lock the latter to said body, said locking member having its opposite end adapted to be engaged by said locking screw, whereby the locking member may be oscillated to grip the tool shank.

5. In a dental instrument, the combination of a body having a socket terminally provided at one end thereof and adapted to receive a tool shank, a threaded socket at the opposite end of the body adapted to receive a locking screw, the stem of which co-operates with said body to provide a handle for the instrument, a locking member pivotally mounted within said body and having one end adapted to be engaged by said locking screw, and the opposite end of said locking member having means thereon adapted to engage and grip a tool shank inserted in said tool-receiving socket, said locking member also having a face adapted to engage the end of said tool shank and move it in an outward direction, when said locking screw is moved out of engagement with said locking member, and pressure is applied to the opposite end of the member.

6. In a dental instrument, the combination of a body having a socket terminally provided at one end thereof, adapted to receive a tool shank, a threaded socket at the opposite end of the body adapted to receive a locking screw, the stem of which co-operates with said body to provide a handle for the instrument, a locking member pivotally mounted within said body and having one end adapted to be engaged by said locking screw, and the opposite end of said locking member having means thereon adapted to engage and grip a tool shank inserted in said tool-receiving socket, said means preventing withdrawal of the tool shank from the body when the locking member is in locking position, said locking member also having means thereon for translating the tool shank in an outward direction when said locking screw is moved out of engagement with said locking member.

In witness whereof, I have hereunto set my hand this 5th day of October, 1927.
